UNITED STATES PATENT OFFICE.

JOSEPH HILBERGER, OF GARFIELD, NEW JERSEY, ASSIGNOR TO NEW JERSEY WORSTED SPINNING CO., OF GARFIELD, NEW JERSEY, A CORPORATION.

YARN-GUIDE FOR SPINNING-MULES.

1,085,864.

Specification of Letters Patent. Patented Feb. 3, 1914.

Application filed June 18, 1913. Serial No. 774,303.

To all whom it may concern:

Be it known that I, JOSEPH HILBERGER, a citizen of Germany, residing at Garfield, county of Bergen, and State of New Jersey, 5 have invented a new and useful Yarn-Guide for Spinning-Mules, of which the following is a specification.

This invention relates to a novel yarn guide for spinning mules which is so constructed that the yarn is automatically severed from the bobbin whenever it is not properly supplied thereto. In this way, a perfect output of uniformly and correctly wound bobbins is obtained, which is necessary for the formation of flawless textile fabrics into which the bobbin threads may be woven or knitted.

In the accompanying drawing: Figure 1 is a cross section through my improved yarn guide and cooperating parts; Fig. 2 a plan of part of a mule-carriage provided with the yarn guide, and Fig. 3 a diagrammatic side elevation of the mule-carriage and coacting parts.

25 The numeral 10 indicates a mule-carriage which receives horizontally reciprocative movement in any suitable manner. Carriage 10 is provided with a series of conventional inclined spindles 11 around which the spun 30 threads 12 are wound in coniform layers, said spindles being driven from a common transverse shaft 13 by means of cords 14.

The strands 15 that go to make up each 35 yarn or thread 12 are delivered from a suitable number of spools 16 and are passed from a common idler 17 between a suitable number of draft rolls 18. During the movement of carriage 10 away from said rolls, the yarn is twisted by means of its fast 40 rotating spindle 11, while during the return movement of the carriage, the thread thus formed is wound on said spindle to form a bobbin 19. The thread formed during each 45 outward movement of carriage 10 is wound upon the previously finished bobbin section in the form of a conical layer 20 by means of an oscillating yarn guide 21, another 50 guide 22 being provided above guide 21.

With my improved construction, guide 21 55 is made in the form of a transverse bar shown to be of oblong rectangular cross section, the bar being mounted in an inclined position relatively to the spindle-axes, so that the yarn passes over one of the short sides or edges 21^a of such bar. In other

words, the longitudinal axis of the bar-cross-section lies substantially in the line dividing the angle that is formed between the two yarn-runs 12^a and 12^b (Fig. 1). Bar 21 is carried by the free ends of a series of sickle-shaped arms 23 fast on a rock shaft 24 that receives oscillating movement through lever 25 and rod 26, so as to properly guide the yarn for winding the desired coniform layers. By the peculiar shape and position of 60 guide 21, any fibers which may occasionally become untwisted from the yarn, cannot possibly wind around the guide, by which winding the yarn would be held back, while slings would be liable to be formed during 65 the inward movement of the carriage.

It is furthermore necessary that all of the bobbins be wound in the same sense, Fig. 2 showing all bobbins to be right-wound. It is obvious that for this purpose all of the 70 bobbins must receive a like motion through their cords 14 from shaft 13. But it frequently happens that upon the breakage of any one cord 14, the operator so refits said cord through carelessness, that in 75 lieu of the right-wound bobbin desired, a left-wound bobbin will result. In order to eliminate any such wrongly wound bobbins, I provide the bar 21 opposite each bobbin 80 with a cutting member located in the range 85 which the yarn would traverse while winding the bobbin-cone in the undesired direction. Thus for the right-wound bobbin shown, in which the yarn sweeps the range 90 $x-y$, the cutting member should be placed opposite the range $x'-y'$, i. e. that range 95 which would be swept by the yarn of a left-wound bobbin. Calling that part a of the bobbin-cone which takes up the yarn from bar 21, the "active" zone, and that part b which would take up the yarn, in case the 100 bobbin would be wound in the opposite sense, the "inactive" zone, the proposition may be so stated, that the cutter on the bar is located directly in front of the inactive zone, while clearing or not extending across the active zone. With the example illustrated, each cutter is formed by providing bar 21 with a sharp-edged slit 27 that extends from edge 21^a a limited distance into the body of 105 said bar. It will be seen that by the construction described, the yarn will be automatically cut, whenever any spindle rotates in the wrong direction, so that the operator may promptly correct the run of the spindle. 110

In order to adapt bar 21 to be set for left-wound spindles as well as for right wound spindles, it is adjustably fitted to arms 23, so that cutters 27 may be made to face either the zones *a* or the zones *b*. For this purpose, bar 21 is shown to be slidably supported in arms 23 and to be held in the selected position by set screws 28.

Cutters 27 have the additional important function of cutting either one or both of a pair of yarns that owing to their whirling motion during twisting, may become entangled between the draft rolls 18 and guide 22. During the subsequent winding of the doubled yarn thus formed, the latter will be laterally deflected from the bobbins and then drawn over the cutters, so that in this way

the winding of defective bobbins is prevented.

I claim:

In a device of the character described, a mule-carriage, a plurality of inclined bobbin-spindles rotatably supported thereby, a rock shaft journaled in the carriage, a plurality of arms secured to the rock shaft, a 25 yarn-guide, means for adjustably securing said guide to the arms, and yarn-cutting means on the guide that are arranged side-wise of the normal paths of the yarns and in front of the inactive zones of the bobbins. 30
